(57) **CLAIM**

The ornamental design for cover with closing arrangement, as shown and described.

DESCRIPTION

FIG. 1 is a front perspective view of a first embodiment of a cover with closing arrangement according to the present invention; the cover with closing arrangement including a closer slide shown in a closed position.

FIG. 2 is a top plan view of the cover with closing arrangement shown in FIG. 1.

FIG. 3 is a side elevation view of the cover with closing arrangement shown in FIG. 1.

FIG. 4 is a front elevation view of the cover with closing arrangement shown in FIG. 1.

FIG. 5 is a rear elevation view of the cover with closing arrangement shown in FIG. 1.

FIG. 6 is a bottom plan view of the cover with closing arrangement shown in FIG. 1; the portions shown in broken lines forming no part of the claimed design.

FIG. 7 is a top plan view of a second embodiment of a cover with closing arrangement according to the present invention; the cover with closing arrangement including a closer slide shown in an open position; the portions shown in broken lines forming no part of the claimed design.

FIG. 8 is a side elevation view of the cover with closing arrangement shown in FIG. 7.

FIG. 9 is a front elevation view of the cover with closing arrangement shown in FIG. 7.

FIG. 10 is a rear elevation view of the cover with closing arrangement shown in FIG. 7; and,

FIG. 11 is a bottom plan view of the cover with closing arrangement shown in FIG. 7.
